UNITED STATES PATENT OFFICE

2,678,191

LIFTING PULL GEAR ENGAGING HOIST

Adolph V. Jensen, Council Bluffs, Iowa

Application June 27, 1951, Serial No. 233,835

1 Claim. (Cl. 254—187)

1

My invention relates to the art of lifting objects. Specifically I have invented a worm and worm gear lifting hoist in which the gear is vertically slidable out of engagement with the worm to permit the quick adjustment of the flexible connector length prior to lifting. The relative movement of the gear to release them is in a direction such that when lifting force is applied the gears are automatically brought into engagement again.

The principal object of my invention is to provide a lifting pull gear engaging hoist the flexible lifting element of which is quickly adjusted to the correct length and thereafter quickly placed in condition to commence lifting operations by applying lifting force.

It is a further object of my invention to provide a lifting pull gear engaging hoist the gears of which are held in meshing relation with each other by a force that varies directly with the amount of the load being lifted.

It is a further object of my invention to provide a lifting pull gear engaging hoist that is extremely compact to make it easy to carry about and capable of the maximum lift in relation to a determined point of support.

A still further object of my invention is to provide a lifting pull gear engaging hoist that is of simple construction thus making it economical to manufacture and use.

These and other objects will be apparent to those skilled in the art.

My invention consists in the construction, arrangement, and combination of the various parts of the device, whereby the objects contemplated are attained as hereinafter more fully set forth, pointed out in my claim, and illustrated in the accompanying drawings, in which:

Fig. 1 is a perspective view of my lifting pull gear engaging hoist with dotted lines showing the adjusting use of the crank handle.

Fig. 2 is a cross-sectional view of my device taken on the line 2—2 of Fig. 1.

Fig. 3 is a side elevation view of my device with a concealed part shown with broken lines, and

Fig. 4 is a longitudinal sectional view of my device taken on the line 4—4 of Fig. 2.

Referring to the drawings, I have used the numeral 10 to designate the main frame of the hoist. I have shown it for purposes of illustration as being a single piece of sheet metal formed into a rectangular element open at both ends. The free ends of the sheet are joined in some appropriate manner as by the screws 11. A worm 12 is rigidly secured to a shaft 13, or formed

2

integrally therewith, that is appropriately journaled in a pair of spaced apart bearings 14. These bearings are rigidly secured to frame 10 in any suitable manner as by the screws 15 or the like. Each end of shaft 13 has a squared portion 16 that fits a similarly shaped well in crank handle 17.

A worm gear designated 18 is used to form one side of a drum 19 on which the cable 20 or other flexible lifting connector element is wound during lifting operations and for storage. The cable is prevented from slipping off the other side of drum 19 by side plate 21. The outside ends of the drum and worm gear mechanism form a bearing end 22 and an adjusting drive 23. All these parts that revolve with the drum are here shown as formed integrally but that is not essential to my invention. The only necessary feature is that the adjusting drive, the drum and the worm gear be rigidly secured together so that torque applied to one is equally applied to the others.

The drum assembly is mounted in a channel member 24 that is small enough to fit inside of frame 10 as shown in Fig. 2. Member 24 embraces the drum and worm gear assembly as shown in Figs. 2 and 4. The member is pivoted for hinged movement in relation to frame 10 by a pair of like pivots designated 25 only one of which is shown in Figs. 1, 3 and 4. A lever member 26 is rigidly secured to or formed integrally with the channel member 24 and extends upwardly through an appropriate slot 27 made in frame 10. The openings in the sides of frame 10 through which the bearing end 22 and adjusting drive 23 extend are elongated ovals as shown in Figs. 1 and 2. The purpose of these elongated openings is to permit the hinging movement of channel member 24 as shown in Fig. 4.

A guide stop member 28 may be rigidly secured to frame 10 if desired, but the guide is not essential to the invention. A means for securing the hoist to a fixed support or the item to be lifted must be provided. A simple and convenient means is eye 29 that is secured to frame 10 by nut 30. A hook or some other appropriate fastening means should be provided at the end of the flexible element, and such means is here shown illustratively as the grommet 31 inserted in the cable loop 32 that is secured by band 33. This completes the description of my device and I will now explain its operation and use.

To use my hoist a suitable support properly located relative to the object to be lifted is dis-

covered. To this support either eye 29 or cable loop 32 is secured. The lever 26 is then moved to the position illustrated in Fig. 4 and the gear 18 is released from worm 12 so that it will free wheel. If it is more convenient to do so, these first two steps may be reversed. When the gear 18 is free to rotate, the cable 20 is easily paid out until the hoist can be connected to the object to be lifted. The crank 17 is then placed on the adjusting drive 23 as suggested by the dotted lines in Fig. 1. Since the slack in the cable is the only load applied to drum 19 at this point the direct drive connection of the crank handle is sufficient leverage and is of course much faster than the geared drive. As the weight of the object to be lifted is applied to the device when all slack has been taken up, the further turning of adjusting drive 23 by crank handle 17 causes a pressure to be exerted on drum 19 that causes it and form gear 18 with it to be slidably moved toward and into meshing relation with worm 12. At this point it is no longer possible to rotate adjusting drive 23 with the crank. The crank is thereafter placed on either of squared ends 16 of shaft 13 and the lifting process carried out by rotating worm 12. The worm and worm gear arrangement will hold any given adjustment. To lower an object, crank handle 17 is rotated in a reverse direction.

Since the worm and worm gear are held in contact with each other in proportion to the amount of tension exerted on the cable, it is not possible to unmesh the gear and the worm to lower a lifted load. However, once the load is lowered, and the hoist is to be prepared for storage; it is possible to free wheel the drum. This permits crank handle 17 to be placed on adjusting drive 23 to reel up the cable rapidly. This hoist is very compact and easily transported when it is reeled up. Also the mechanism is practically fool proof. It is also clear from the foregoing how quickly and easily the hoist is adjusted and prepared for lifting. The fact that the pull exerted during lifting actions holds the gear and the worm toward each other is a considerable safety factor. There is no possibility of the gear and worm becoming unmeshed and dropping a lifted load suddenly to the possible injury of equipment and personnel.

Some changes may be made in the construc-

tion and arrangement of my lifting pull gear engaging hoist without departing from the real spirit and purpose of my invention, and it is my intention to cover by my claim, any modified forms of structure or use of mechanical equivalents which may be reasonably included within their scope.

I claim:

In a lifting device; an open end rectangular frame having a slot opening in its top; a pair of vertically extending centrally arranged slots, one in each side of said frame in alignment with each other; a channel-shaped member pivotally mounted inside said frame and pivoting on an axis eccentric to the slots in said frame sides; said channel-shaped member having holes therein that align with the slots in said frame sides; a drum and worm gear assembly rotatably mounted in said channel-shaped member holes and having portions thereof extending into said slots; a worm rotatably mounted in said frame below said drum and worm gear assembly; a flexible element wound on said drum; a lever secured to said channel-shaped member and extending through the opening in said rectangular frame and beyond said frame for pivoting said channel-shaped member; at least one drive secured to said worm; a drive secured to said drum and worm gear assembly and accessible from the outside of said frame; and a crank handle selectively engageable with said drive; said worm and worm gear being in mesh when said channel-shaped member is pivoted to carry said drum and worm gear assembly to a relatively low position on said frame and disengaged when said channel-shaped member is pivoted to carry said drum and worm gear assembly to a relatively high position on said frame.
